(57) **CLAIM**

The ornamental design for a display screen with animated graphical user interface, as shown and described.

DESCRIPTION

The file of this patent contains at least one drawing executed in color. Copies of this patent with color drawings will be provided by the Office upon request and payment of the necessary fee.

FIG. 1 is a front view of a display screen with animated graphical user interface showing the first image of our new design; and,

FIG. 2 is a front view of a second image thereof.

The appearance of the animated graphical user interface sequentially transitions between the images shown in FIGS. 1-2. The process or period in which one image transitions to another image forms no part of the claimed design.

The outermost broken lines in the drawings illustrate a display screen. The remaining broken lines in FIG. 2 illustrate portions of the graphical user interface. None of the broken lines form part of the claimed design.
